STEERING WHEEL

Clifford G. Schroeder, 4685 Harris Road,
Brecksville, Ohio 44141

Filed Apr. 4, 1966, Ser. No. 1,758

Term of patent 14 years

(Cl. D14—30)

Fig. 4

FIGURE 1 is a plan view of a steering wheel embodying my new design, it being understood that the full line portion is repeated throughout the circumference of the rim of the wheel shown by means of broken lines;

FIGURE 2 is a side elevational view of the same;

FIGURE 3 is an enlarged cross-sectional view taken through the line 3—3 of FIGURE 1; and

FIGURE 4 is an enlarged view of a portion of the rim of the said wheel, looking in the direction of the arrows 4—4 of FIGURE 1.

The dominant features of my design reside in the portions shown in full lines.

I claim:

The ornamental design for a steering wheel, substantially as shown and described.
